UNITED STATES PATENT OFFICE.

ALFRED J. THOMAS, OF BOSTON, MASSACHUSETTS.

INSEAM-TRIMMING MACHINE.

1,296,570.

Specification of Letters Patent.

Patented Mar. 4, 1919.

Application filed June 18, 1918. Serial No. 241,072.

To all whom it may concern:

Be it known that I, ALFRED J. THOMAS, a citizen of the United States of America, and a resident of Boston, in the county of Suffolk and State of Massachusetts, have invented certain new and useful Improvements in Inseam-Trimming Machines, of which the following is a specification.

This invention relates to inseam trimming machines, and particularly to machines of this class in which a rotary disk knife is used to trim off the surplus material of the upper, welt, and sole-lip after said upper and welt have been sewed to said sole-lip.

The object of the present invention is to produce a machine for this purpose by which the inseam may be more effectively trimmed, and particularly in the portions thereof where there are sharp curves.

The invention consists of providing the machine with a rotary disk knife, the front face of which is beveled off to form a cutting edge.

It further consists of an adjustable guide having a trough therein which serves as a guide to direct the material to the trimming knife.

It further consists in providing means for sharpening the knife during the trimming operation.

The invention further consists in certain novel features of construction and arrangement of parts which will be fully understood by reference to the description of the drawings and to the claims hereinafter given.

For the purpose of illustrating the invention one preferred form thereof is illustrated in the drawings, this form having been found to give satisfactory and reliable results, although it is to be understood that the various instrumentalities of which the invention consists can be variously arranged and organized and the invention is not limited to the precise arrangement and organization of these instrumentalities as herein shown and described, except as required by the scope of the appended claims.

Of the drawings:

Figure 1 represents a plan of an inseam trimming machine embodying the principles of the present invention.

Fig. 2 represents a longitudinal section on line 2, 2 on Fig. 1.

Fig. 3 represents a vertical transverse section on line 3, 3 on Fig. 2.

Fig. 4 represents an elevation of the left end of the machine and

Fig. 5 represents a sectional detail to be hereinafter described.

In the drawings, 10 is the top of a column to which is secured a frame 11, having mounted in the base thereof an oscillating shaft 12, and provided at the top with aligned bearings 13, in which is revolubly mounted the shaft 14.

The shaft 14 is parallel to the oscillating shaft 12, and has at one end thereof an enlarged cone-shaped end 15 fitted to the cone-shaped bore of a bushing 16 in one of the bearings 13.

To the end 15 of the shaft 14 is secured a disk knife 17 by means of a flat headed screw 18 threaded to the end 15 as indicated in dotted lines in Fig. 2.

This knife 17 is circular and has its outer face beveled off at 19 to form the cutting edge 20.

It has been found in practice that much better results may be obtained in trimming the inseam when a knife is used having the bevel 19 on the outer face, than can be obtained by the use of a knife having the bevel on its rear face.

Between the bearings 13 the shaft 14 has secured thereto a driving pulley 21 for imparting rotary movement to said shaft 14.

On the left hand end of the shaft 14, as viewed in Fig. 2, are secured the nuts 22-23, and between the nut 23 and one of the bearings 13 is a fiber washer 24.

The nuts 22-23 prevent end movement of said shaft 14, and as the end 15 or bushing 16 becomes worn these nuts may be adjusted to take up the wear, thereby providing a steady rotary movement of the knife 17 at all times.

The shaft 14 has a reduced end 20 to which there is secured by set screws 26, a disk 27 having an outwardly extending hub 28.

A tubular member 29 surrounds the hub 28 and extends beyond the end thereof, and

this tubular member 29 has mounted in its outer end a closure 30 provided with a revoluble ball 31 centrally disposed therein.

On the left end of the oscillating shaft 5 12, as viewed in Fig. 2, is secured by set screw 32 a lever 33, the upper end of which is provided with a curved portion 34 concentric to the axis of the shaft 12.

This curved portion 34 has secured to its 10 inner face by screws 35 (see Fig. 1) a cam plate 36 the beveled portion 37 of which is normally in contact with the ball 31.

The tubular member 29 is adapted to 15 slide endwise on the hub 28, and has secured thereto a driving pulley 38 having a depression 39 in one face into which the disk 27 projects, and in this depression between said disk and pulley is a leather washer 40.

20 When the lever 33 is moved forward by the oscillation of the shaft 12 the cam surface 37 will force the pulley 38 into contact with leather washer 40 on the disk 27 with sufficient friction to cause the rotary 25 movement of the shaft 14 to be transmitted through said disk 27 to the pulley 38.

In the forward movement of the lever 33 the cam surface 37 acting on the ball 31 will cause the clutch members 27-38 to 30 be brought into engagement, and then by the continued forward movement of the lever, the face 41 will be brought into contact with the ball 31 and retain said clutch members in engagement.

35 To the right hand end of the shaft 12, as viewed in Figs. 1 and 2, is secured a jointed arm 42, 43, the section 43 being pivoted at 44 to the rear end of the section 42 in such a manner that said section may be clamped 40 in adjusted position at any angle relatively to the section 42.

The outer end of the section 43 is provided with a slot 45 in which is adjustably secured a stud 46.

45 A fiber washer 47 surrounds the stud 46 and rests on the top face of the section 43.

Above the washer 47 and surrounding the stud 46 are two anti-friction devices 48-49 separated by a sleeve 50.

50 Surrounding the sleeve 50 and driven on to the anti-friction devices 48-49 is a barrel 51 having a reduced end 52 on which is mounted an emery wheel 53 clamped against the end of the body of the barrel 51 by means of the nut 54.

A passage 55 extends through the reduced end 52 into the interior of the barrel thereby providing means for the admission of a suitable lubricant, this passage 55 being 60 closed by the threaded plug 56.

The upper end of the stud 46 is upset to prevent the inner rings 57 of the anti-friction devices 48-49 and sleeve 50 moving endwise of the stud 46.

Inasmuch as the outer ring 58 of each 65 anti-friction device is driven into the barrel 51 it is obvious that it would be impossible for the emery wheel 53 to be lifted while at same time it is free to rotate about the axis of the stud 46.

70 By this construction of bearing the emery dust is effectually prevented from entering the bearing and thereby interfere with the proper operation of the machine.

The barrel 51 has secured thereto a 75 grooved pulley 59 adapted to be driven from the pulley 38 by means of the belt 60.

This belt 60 is endless and passes partially around the intermediate pulleys 61 and 62, revolvably mounted on the trunnions 80 63 of a block 64, one trunnion 63 being secured in a member 65 adjustably mounted on an arm 66 extending rearwardly from the frame 11. This arm may be adjusted about its axis and locked in adjusted position by means of the set screw 67, thereby varying the angle of the intermediate pulleys 61, 62.

85 The arm 66 may also be moved endwise to take up any slack in the belt 60.

90 The section 42 of the arm supporting the emery wheel also has a forward extension 68 adapted to be operated by a treadle (not shown) to oscillate the shaft 12 and at the same time move the emery wheel 53 into 95 position to sharpen the beveled edge 19 of the disk knife 17.

99 This oscillation of the shaft 12 will move the lever 33 so that the clutch members 27, 38 will become engaged, and rotary 100 movement will be transmitted from the shaft 14 to the emery wheel 53.

The lever 33 is provided with a wing 70 having a rubber buffer 71 therein which is normally held in contact with the rib 72 of 105 the frame 11 by means of the usual treadle spring.

The frame 11 is provided with a groove 73 closed by a plate 74 and having mounted thereon a bar 75 which is adapted to be 110 adjusted endwise and locked in adjusted position by means of the set screw 76.

The forward end of the bar 75 has an upwardly projecting extension 77, the upper end of which is provided with a triangular groove in which is positioned the shank 78 of the work guide 79.

A slit 80 extends from the triangular groove to the opposite edge of said extension 77, and a clamping bolt 81 extends 120 across said slit and is adapted to be adjusted to clamp the work guide 79 to the extension 77.

125 By loosening the bolt 81 the work guide 79 may be adjusted endwise and then locked in position.

This work guide 79 is provided with a peripheral groove 82 into which the knife

edge 20 extends, and communicating with the top of this groove 82 is a trough 83 extending rearwardly therefrom.

This trough 83 is so curved and shaped that when the surplus material is being trimmed, and the lasted shoe is being moved approximately in the direction of the arrow *a*, Fig. 1, the edges of the welt, upper and sole lip will be moved away from the sole 10 into proper position to be presented to the knife edge 20.

By varying the position of the emery wheel 53 relatively to the section 43, and by moving the section 43 about the pivot 44, 15 the inclination of the bevel 19 may be changed as desired.

The bar 75 is provided with a slot 84 in which is positioned the shank 85 of a block 86, having pivoted thereto a bifurcated claw 20 87 adapted to be inserted beneath the end of the welt of the shoe, with the stitches in the space between the two fingers of said claw.

When the claw 87 has been inserted in this manner beneath the welt, the lasted shoe is moved with the claw 87 about the pivot of the latter into position so that the end of the welt may be chamfered off by the knife 17.

As soon as the end of the welt has been cut off, the lasted shoe is removed from the claw 87, and said claw will be returned to its normal position by means of the spring 88 interposed between said claw and said block 86.

By means of this machine the inseam may be trimmed off in an even manner throughout its entire length, the operator holding the sole against the outer end of the 40 guide 79.

If the knife requires sharpening the emery wheel may be brought into contact with the bevel 19 to accomplish this sharpening without stopping the machine.

When the inseam has been trimmed the 45 ends of the welt may be butted off on the same machine, thus saving expense and delay in finishing the shoe.

It is believed that the operation and many 50 advantages of the machine will be fully understood without further description.

Having thus described my invention, I claim:

1. In an inseam trimming machine, a rotary disk knife having its outer face beveled to form a cutting edge; and a non-revoluble work guide having a peripheral groove extending partially about the axis thereof and into which extends the cutting edge of said 55 knife.

2. In an inseam trimming machine, a revoluble shaft, a rotary disk knife thereon; an emery wheel; a work guide; and means 60 slidably mounted on said shaft and adapted

to be driven thereby to rotate said emery wheel when the latter has been moved into position to sharpen the knife edge.

3. In an inseam trimming machine, a revoluble shaft, a disk knife secured to one end thereof; a clutch member secured to the opposite end of said shaft; a second clutch member slidable endwise of said shaft; and an oscillating arm having a cam face thereon adapted to move said slidable clutch member into engagement with the 75 clutch member on said shaft.

4. In an inseam trimming machine, a revoluble shaft, a disk knife secured to one end thereof; a clutch member secured to the opposite end of said shaft and having an 80 outwardly extending hub; a second clutch member slidable endwise of said hub; and an oscillating arm having a cam face thereon adapted to move said slidable clutch member into engagement with the clutch 85 member on said shaft.

5. In an inseam trimming machine, a revoluble shaft, a disk knife secured to one end thereof; a clutch member secured to the opposite end of said shaft and having an 90 outwardly extending hub; a second clutch member slidable endwise of said hub and having a tubular extension; a ball revolvably mounted in said extension; and means acting on said ball for forcing said slidable 95 clutch member into engagement with the clutch member on said shaft.

6. In an inseam trimming machine, a revoluble shaft, a disk knife secured to one end thereof; a clutch member secured to the opposite end of said shaft and having an outwardly extending hub; a second clutch member slidable endwise of said hub and having a tubular extension; a ball revolvably mounted in said extension; and an 100 oscillating arm having a cam face thereon coacting with said ball to force said clutch members into engagement.

7. In an inseam trimming machine, a revoluble shaft, a disk knife secured to one end thereof; a disk secured to the opposite end of said shaft; a pulley slidable endwise of said shaft and adapted to coact with and be driven by said shaft; an oscillating shaft provided with means for forcing said pulley 110 against said disk; an arm on the opposite end of said oscillating shaft; an emery wheel mounted on said arm; and means for transmitting rotary movement from said pulley to said emery wheel.

8. In an inseam trimming machine, a revoluble shaft, a disk knife secured to one end thereof; a disk secured to the opposite end of said shaft; a pulley slidable endwise of said shaft and adapted to coact with and be driven by said shaft; an oscillating shaft provided with means for forcing said pulley against said disk; an arm on the opposite 125

- end of said oscillating shaft; a stud secured to said arm; an emery wheel revolvably mounted on said stud; and means for transmitting rotary movement from said pulley 5 to said emery wheel.
9. In an inseam trimming machine, a revolvble shaft; a disk knife secured to one end thereof; a disk secured to the opposite end of said shaft; a pulley slidably endwise 10 of said shaft and adapted to coact with and be driven by said shaft; an oscillating shaft provided with means for forcing said pulley against said disk; an arm on the opposite end of said oscillating shaft; a stud secured 15 to said arm; a barrel revolvably mounted on said stud; an emery wheel secured to said barrel; and means for transmitting rotary movement from said pulley to said barrel.
10. In an inseam trimming machine, a revolvble shaft; a disk knife secured to one end thereof; a disk secured to the opposite end of said shaft; a pulley slidably endwise of said shaft and adapted to coact with and be driven by said shaft; an oscillating shaft provided with means for forcing 20 said pulley against said disk; an arm on the opposite end of said oscillating shaft; a stud secured to said arm; a barrel revolvably mounted on said stud; anti-friction members 25 interposed between said barrel and stud; an emery wheel secured to said barrel; and means for transmitting rotary movement from said pulley to said barrel.
11. In an inseam trimming machine, a revolvble shaft; a disk knife secured to one end thereof; a disk secured to the opposite end of said shaft; a pulley slidably endwise of 30 said shaft and adapted to coact with and be driven by said shaft; an oscillating shaft; a lever on one end of said oscillating shaft provided with means for forcing said pulley against said disk; a hinged arm on the opposite end of said oscillating shaft; an emery wheel mounted on said arm; and means for 35 transmitting rotary movement from said pulley to said emery wheel.
12. In an inseam trimming machine, a rotary disk knife and a work guide having a peripheral groove into which extends the cutting edge of said knife, and provided 40 with a trough communicating with one end of said groove and inclined rearwardly therefrom.
13. In an inseam trimming machine, a rotary disk knife having its outer face beveled to form a cutting edge; a guide parallel to the axis thereof and having a peripheral groove into which extends the cutting edge 45 of said knife; and means for adjusting said guide endwise.
14. In an inseam trimming machine, a rotary disk knife; a guide parallel to the axis thereof and having a peripheral groove into which extends the cutting edge of said knife; 50 a support for said guide in the rear of and 65 parallel to the rear face of said knife; means for adjusting said support endwise; and means for adjusting said guide endwise.
15. In an inseam trimming machine, a revolvble shaft; a rotary knife secured to one end thereof; a revolvble emery wheel; means for moving said emery wheel into position to sharpen the knife; a barrel to which said emery wheel is secured; two separate rings in opposite ends of said barrel; a stud; two 70 75 separate rings on said stud; and anti-friction members interposed between the stud rings and the barrel rings.
16. In an inseam trimming machine, a revolvble shaft; a rotary knife secured to one end thereof; a revolvble emery wheel; means for moving said emery wheel into position to sharpen the knife; a barrel to which said emery wheel is secured; two separate rings in opposite ends of said barrel; a stud; two 80 85 separate rings on said stud; means on said stud preventing end movement of the rings thereon; and anti-friction members interposed between the stud rings and the barrel rings.
17. In an inseam trimming machine, a revolvble shaft; a rotary knife secured to one end thereof; a revolvble emery wheel; means for moving said emery wheel into position to sharpen said knife; a barrel 90 95 closed at the upper end and to which said emery wheel is secured; two separate rings in opposite ends of said barrel; a stud; two separate rings on said stud; and anti-friction members interposed between the stud 100 rings and the barrel rings.
18. In an inseam trimming machine, a revolvble shaft; a rotary knife secured to one end thereof; a revolvble emery wheel; means for moving said emery wheel into position to sharpen said knife; a barrel provided with a reduced upper end to which said emery wheel is secured; two separate rings in opposite ends of said barrel; a stud; two separate rings on said stud; and anti-friction members interposed between the stud 105 110 rings and the barrel rings.
19. In an inseam trimming machine, a revolvble shaft; a rotary knife secured to one end thereof; a revolvble emery wheel; means for moving said emery wheel into position to sharpen said knife; a barrel to which said emery wheel is secured closed at the upper end and having a normally 115 closed passage in said upper end for the admission of lubricant to the interior of said barrel; two separate rings in opposite ends of said barrel; a stud; two separate rings on said stud; and anti-friction members interposed between the stud rings and the barrel 120 125 rings.
20. In an inseam trimming machine, a rotary disk knife; a bifurcated claw ad-

jacent to said knife the fingers of which are adapted to straddle the welt stitches; and means whereby said claw may be moved into position to permit the knife to cut off the 5 end of the welt at an angle to the face thereof.

21. In an inseam trimming machine, a rotary disk knife; a bifurcated claw adjacent to said knife the fingers of which are adapted to straddle the welt stitches; said claw being pivotally mounted so that it may be moved into position to permit the knife to cut off the end of the welt at an angle to the face thereof.

15 22. In an inseam trimming machine, a rotary disk knife; a bifurcated claw adjacent to said knife the fingers of which are adapted to straddle the welt stitches; said claw being pivotally mounted so that it may be moved into position to permit the knife to cut off the end of the welt at an angle to the face thereof; and means for returning 20 said claw to its normal position.

23. In an inseam trimming machine, a ro-

tary disk knife; a bifurcated claw adjacent 25 to said knife the fingers of which are adapted to straddle the welt stitches; means for adjusting the position of said claw relatively to said knife; and means whereby said claw may be moved into position to 30 permit the knife to chamfer off the end of the welt.

24. In an inseam trimming machine, a rotary disk knife; an adjustable bar parallel to the rear face of said knife and provided with a transverse slot therein; a block 35 adjustably mounted in said slot; a bifurcated claw pivoted to said block with a face thereof adjacent the cutting edge of said knife; and a spring interposed between said block and claw and normally retaining said claw free from the knife edge.

Signed by me at 4, Post Office Square, Boston, Mass., this 9th day of April, 1918.

ALFRED J. THOMAS.
